United States Patent Office

Des. 200,198
Patented Feb. 2, 1965

200,198

STRAP FASTENER

Ilmar J. Vilcins, Oak Park, and Hobart P. Young,
Winnetka, Ill., assignors to Signode Steel Strapping
Company, a corporation of Delaware

Filed Apr. 29, 1963, Ser. No. 74,660

Term of patent 14 years

(Cl. D17—5)

We claim:

The ornamental design for a strap fastener, substantially as shown and described.
